UNITED STATES PATENT OFFICE.

HAROLD PEARSON HIRD, OF DEWSBURY, ENGLAND.

APPARATUS FOR THE CARBONIZATION OF COAL AND THE LIKE.

Application filed March 21, 1922. Serial No. 545,496.

To all whom it may concern:

Be it known that I, HAROLD PEARSON HIRD, a subject of the King of Great Britain and Ireland, residing at Moor End, Dewsbury Moor, Dewsbury, Yorkshire, England, have invented new and useful Improvements in Apparatus for the Carbonization of Coal and the like, of which the following is a specification.

10 This invention relates to improvements in apparatus for the carbonization of coal, shale, peat, lignite, and the like, and my object is to construct and arrange in connection with suitable retorts a device or devices which will keep an open way in the material under carbonization within the retort. The device or devices may vary somewhat and comprise one or more rotating blades or like arranged within the retort 20 in such wise that the material is left in a comparatively thin layer against the sides of the retort, thus facilitating the carbonization of the same, and leaving a preferably central opening or way through which 25 the gaseous products of carbonization may pass to the exit of the retort thus preventing unnecessary decomposition of the products.

The rotating blades or like may also move 30 and mix the material, or I may use a moving member or members within the mass adapted to form and maintain a way or ways through the material.

In describing my invention in detail reference is made to the accompanying sheet of drawings in which Fig. 1. represents a sectional elevation of a retort with my apparatus applied thereto.

Fig. 2. represents a section on line *a. b.* in Fig. 1.

Fig. 3. represents a similar view to that shown in Fig. 1 of a modified form of apparatus and

Fig. 4. represents sections of other forms of channel formers.

To carry my invention into effect I may use any number of retorts by preference circular in shape and suitably disposed and heated after the usual manner. I will for 50 clearness describe my arrangement and apparatus as applied to one retort.

Each retort *R*, in the form shown in Figs. 1 and 2 will have a suitable shaft *A* by preference central, and I have found in practice that instead of adding blades thereto the

shaft itself may be of such a cross section as to give the desired action and form a passage up which the gaseous products of carbonization may pass to the outlet *R'* a suitable section being square as shown in Figs. 1 and 2 or of any other section which in rotating or moving will form the desired passage. Further examples are shown in Figs. 3 and 4. The shaft will be suitably rotated, one method being shown in Fig. 1. A bearing *A'* for the shaft may be formed in the retort *R* and the retort may be of greater diameter at one end than the other. The fuel or like may be fed to the retort through the inlet *R²* by a spiral feed or other suitable and usual means. The ordinary system of carbonization is to apply the heat exterior to the retort, and under heat the contents of the retort tend to solidify leaving the escaping gases to make their escape along the sides of the retort and these gases in ascending are to some extent decomposed especially where the temperature is high. It has been customary therefore to use high temperatures at the bottom of the retort and lower temperatures higher up, and owing too, to the thickness of the mass within the retort carbonization, to be complete, takes a considerable time. Whereas by forming a central passage within the retort by means of a continually moving device, the escaping gases instead of passing up or along the side of the retort nearest the heat pass inwards to the central opening giving off their sensible heat to the mass as they pass through and in ascending give heat to the incoming material and pass away at the outlet, therefore I may effect carbonization using a high temperature outside the retort and yet obtain low temperature carbonization within the retort. This process does not tend to produce tar, but in lieu thereof produces oil.

The moving action of the central shaft or like will also have a grinding action which will tend to break up the material and also to some extent press the escaping gases back into the mass at a point or points where the temperature is lowest within the retort and so assist in the carbonization process.

The before mentioned shaft may be of plain section as before described so long as in moving it makes a passage for the gases to pass away to the outlet. I may also provide same with blades here and there to

reach nearer to the sides of the retort, and in order to economize power these blades or like will by preference be cone shaped. These devices are indicated by dotted lines as at A² Fig. 1. In some forms of device I may find it necessary to also move the shaft up and down (or in and out) to give as it were a ramming movement. Such movement will be slow and steady and may be effected by means of an eccentric connection A³ secured to a slow running shaft A⁴, and the rotary movement will be carried out by means such as by a bevel wheel A⁵ mounted slidably on the shaft A. If this latter shaft is square the driving means will be understood and in Fig. 1 a suitable arrangement is shown. The connection to the eccentric being one which will allow the shaft to turn such as a ball and socket joint. In Fig. 3, I have shown a modified form of apparatus comprising a shaft such as A^x tapering to a point or nearly so. This member A^x will be connected to suitable driving gear such as that before described and arranged to rise and fall, the rising motion forming the passage for the ascension of the gases, and the falling motion closing such passage. This action while giving substantially the same effect as that of the shaped shaft tends to check the gases rather more and give somewhat additional low temperature carbonization within the retort, and also tends to compress such gases and the carbonized material. In order to facilitate the pressing down and withdrawal of this member, it may also revolve after the manner of the shaft A either continually in one direction, or first in one direction and then in another, means for giving this motion are well known. By combining with a suitable retort means for the formation of an interior passage by a moving shaft or like substantially as hereinbefore described, I may use very high temperatures outside the retort without the detriment or deleterious decomposition of the products, I may thus increase the rate of carbonization and the conse-

quent removal of the products and I obtain greater yield per charge of oils and motor spirit. Where retorts of large diameter are employed I may have several of the passage forming devices, and in addition to the heated gases rising or passing along such passage I may heat up the mass by a stream or streams of hot relatively inert gases supplied from an external source, and in cases where exterior heat is not available the hot gases may be used for internal heating.

What I claim as my invention is:—

1. A carbonizing apparatus, comprising a retort for receiving the material to be carbonized, a shaft mounted for rotation in said retort and extending the entire length of the retort, said shaft being of such cross-section as, by its rotation, to form and maintain open a continuous passageway through the material in the retort, and means for imparting rotary motion to said shaft. 60

2. A carbonizing apparatus, comprising a retort for receiving the material to be carbonized, a shaft mounted for rotation in said retort and extending substantially the entire length of the retort, said shaft being square in cross-section thereby, by its rotation, to form and maintain open a continuous passageway through the material in the retort, and means for imparting rotary motion to said shaft. 75

3. A carbonizing apparatus, comprising a retort for receiving the material to be carbonized, a shaft mounted for rotation in said retort and extending substantially the entire length of the retort, said shaft being square in cross-section thereby, by its rotation, to form and maintain open a continuous passageway through the material in the retort, means for imparting rotary motion to said shaft, and means for imparting a reciprocatory motion to the shaft. 80

In testimony whereof I have signed my name to this specification.

HAROLD PEARSON HIRD.

Witness:

CLIVE WAUGH.
